FIG. 4. Inventor.

FRANK GUY.
By Atty N. Dubois.

UNITED STATES PATENT OFFICE.

FRANK GUY, OF SPRINGFIELD, ILLINOIS.

WATER-FEED APPLIANCE FOR ACETYLENE-LAMPS.

1,356,711.

Specification of Letters Patent. Patented Oct. 26, 1920.

Application filed November 4, 1918. Serial No. 261,044.

To all whom it may concern:

Be it known that I, FRANK GUY, a citizen of the United States, residing at Springfield, in the county of Sangamon and State 5 of Illinois, have invented a new and useful Water-Feed Appliance for Acetylene-Lamps, of which the following is a specification.

The invention relates primarily to feed 10 appliances for acetylene lamps such as are commonly used by miners and others, but may be applied with equal advantage to other lamps adapted to generate acetylene gas by the controlled application of water to 15 calcium carbide.

The feed attachment herein set forth is 20 designed for use on lamps of different makes and may be made and sold as a separate article of manufacture.

Acetylene lamps of the type to which this 25 invention relates generally comprise a water reservoir, a carbide box, a feed tube intercommunicating between the water reservoir and the carbide box to convey water from the reservoir into the box and a valve controlling the flow of water through the tube. In some instances the valve is at the lower end of the tube, and in other instances it is at the upper end of the tube. It is well known to 30 persons skilled in the art that efflorescence results from the contact of the water with the carbide, causing a moist ash to accumulate in and around the lower end of the tube, or around the valve at the lower end of the 35 tube as the case may be, and when the ash dries it forms incrustation which often completely chokes the tube so that water cannot pass through it; or surrounds the valve and causes it to stick on the valve seat thus stopping 40 the flow of water through the tube so that it is necessary to frequently rotate the valve to break up the incrustation and restore the feed.

A prime purpose of my invention is to 45 overcome these difficulties. More specific purposes of my invention are: to provide in connection with the feed tube, a plurality of coördinated receiver tubes adapted to receive water well above the ash in the box 50 and apply it on a distributor extending through the ash into the carbide; to provide simple and effective means for connecting the receiver tubes with the feed tube so that the latter may be manually rotated on the former; and to provide a distributor of a 55 form specially adapted to distribute the

water applied thereto, and also adapted to facilitate the rotation of one of the receiver tubes.

The invention is illustrated in the annexed 60 drawing to which reference is hereby made, and will now be described, and finally recited in the claim.

Figure 1 is an elevation of the water-feed 65 appliance in place on the feed tube of an acetylene lamp, partly in section; Fig. 2 is an enlarged vertical axial section, through the feed attachment and the feed tube on the line X. X. of Fig. 1; Fig. 3 is an elevation of a feed-attachment of modified construction 70 in place on the feed-tube of an acetylene lamp, shown partly in section;

Fig. 4 is an enlarged vertical axial section on the line Y. Y. of Fig. 3;

Fig. 5 is an enlarged horizontal section 75 through the outer receiver tube, the springy members of the intermediate receiver tube, and the feed tube on the line Z. Z. of Fig. 2; and

Fig. 6 is an enlarged horizontal section 80 through the outer receiver tube, the springy members of the inner receiving tube and the feed tube, on the line W. W. of Fig. 4.

The same reference numerals designate 85 the same parts in all the views.

The lamp may be of any suitable material, preferably light sheet metal, strong enough to withstand the pressure of the generated gas and preferably comprises a water reservoir 1, a carbide box 2, a stationary diaphragm 3, united with the reservoir, a screw member 5 on the reservoir 1, a complemental screw member 6 on the box 2 engaging with the screw member 5 to connect the box with the reservoir so that box may be detached 90 to admit carbide into the box, an opening 7 to admit water to the reservoir, a cap 8 closing the opening 7, a vertical feed-tube 9 permanently attached to the diaphragm and having at one end a flared valve seat 12, a 100 tapered valve plug 13 fitted to the seat 12, a valve stem 14 permanently attached to the plug 13, and having a screw-threaded part 15, adapted to engage in a female screw 16 on the top of the reservoir, and a handle 17 105 usable for rotating the valve stem in one direction to press the plug 13 against the seat 12 to close the valve, and rotating it in the opposite direction to remove the plug from the seat to open the valve, more or less, according to circumstances.

I prefer to use a valve 13 as described for

first control of the water in the tube but the feed regulation would be effective without the valve and it obviously may be omitted without departure from my invention.

5 The feed tube 9 has a series of circumferential grooves 23, 24, 25. The feed-attachment proper comprises three co-axial and slightly tapered receiver tubes 18, 28, and 31, adapted to slide and rotate on the feed-
10 tube and adapted to receive water from the feed-tube and conduct it downward along the respective receiver tubes in a manner to be hereinafter described. In practice the tubes 18, 28, and 31 will be of thin non-cor-
15 rosive metal spaced slightly apart from each other to permit a very restricted flow of water between the tubes. For the sake of clear illustration the thickness of the walls of the tubes and the width of the spaces be-
20 tween the tubes are greatly exaggerated in the drawing, it is expressly designed how-
ever that the spaces between the tubes shall be so restricted that the quantity of water passing between and around the tubes shall
25 be just sufficient for the proper generation of gas when applied to the mass of carbid 36 in the box 2.

The receiver tube 18 has at its upper end 30 springy fingers 26, separated by spaces 27, the fingers being adapted to engage in the groove 24 to support the receiver tube on, and permit it to rotate around the feed tube. At the lower terminal of the tube 18 is a 35 tapered member 19 adapted to easily enter and conduct water to the carbid, and also serving to close the end of the tube and form a chamber 20 to contain water, which in due course fills the tube, overflows through the spaces 27 between the fingers 26, and flows 40 downward along the outer surface of the tube.

A circumferential ledge 21, around the lower part of the receiver tube, is adapted to catch and diffuse water dropping from 45 all the receiver tubes 18, 31, and 28. Flutings 22 in the member 21 facilitate the manual rotation of the tube and cause uniform distribution of the water.

The outer receiver tube 28 has springy 50 fingers 29 spaced apart from each other and adapted to engage in the groove 23 to support the receiver tube and permit it to rotate on the feed tube 9. The intermediate receiver tube 31 has springy fingers 32 sepa-
55 rated by spaces 33 and adapted to engage in the groove 25 to support the receiver tube and permit it to rotate on the feed-tube 9.

It will be noted that there are three outlets for the water, one above the other. If 60 the lower opening becomes clogged, the intermediate opening will still admit a suitable quantity of water, and if the lower opening and the intermediate opening both become clogged the upper opening will still
65 admit a sufficient quantity of water. The

openings at the top of the respective receiver tubes permit the escape of air and obviate air pockets in the tubes which might stop the flow of water in the tubes if air vents were not provided. The springy connec-
75 tions of the receiver tubes with the feed-tube of the lamp admit of placing the receiver tubes on the feed tube and rotating them by hand, or removing them from the feed-tube by hand.

I have shown and described a preferred embodiment of my invention comprising a feed-tube, a valve seating on the lower end of the feed-tube, three coördinated receiving tubes, and a distributor. The modified 80 embodiment of the invention, illustrated in Figs. 3, 4 and 6, comprises a feed-tube 9 provided with circular grooves 24 and 25, a valve 37 seating on the upper end of the feed-tube, two coördinated receiver tubes 18 85 and 31 having springy fingers, and a distributor 19 having a chamber 20 and a ledge 21. The receiver tubes 18 and 31 are rotative on the feed-tube 9 as already described.

90 Mode of operation.

Upon opening the valve 13, water from the feed-tube 9 will fill the receiver tube 18 and overflow through the spaces 27 between the fingers 26 and will trickle downward on the outer surface of the tube 18 and fall upon the ledge 21 and gravitating downward from the ledge will be diffused in the mass of carbid. If the space 34 between the receiver tubes 18 and 31 should become so 100 clogged as to stop the flow of water downward along the outer surface of the receiver tube 18, the over-flow from the tube 18 would fill the space 34, and would overflow the upper end of the intermediate receiver tube 31, 105 and would trickle slowly down the outer surface of the tube 31, and trickling on the ledge 21 would be diffused in the mass of carbid. If the space 35 between the receiver tubes 31 and 28 should become so clogged 110 as to stop the escape of water from the space, the water accumulating in the space would overflow the outer receiver tube 28 and would trickle downward along its outer surface and would fall on the ledge 21 and 115 be distributed in the mass of carbid.

To break up the accretion and remove it from the spaces 34 and 35, the reservoir will be detached from the carbid box, the outer tube 28 will be held in one hand and the intermediate tube 31 will be rotated with the other hand to break the accretion so that upon turning on the water, it may be easily washed out.

The operation of the attachment of modified construction will be obvious from the foregoing description.

The use of a plurality of coördinated receiver tubes co-acting with one distributor 13 obviates the risk of frequent stoppage of the

flow of water and assures practically uniform generation of gas. This feature is of great practical advantage.

I do not restrict my claims to the precise construction disclosed since minor structural changes clearly within the scope of my invention will readily occur to persons skilled in the art.

Having fully described my invention, what 10 I claim as new and desire to secure by Letters Patent is:

A water-feed appliance for acetylene lamps, comprising a feed tube having external circumferential grooves; a vertical 15 series of manually rotative coördinated re-

ceiver tubes open at both ends and having spring connections engaging in the circumferential grooves of the feed tube; and a cone-pointed circular distributor having a fluted ledge extending outwardly beyond the circumference of the uppermost receiver tube and adapted to receive over-flow from any of the receiver tubes.

In witness whereof I have hereunto signed my name at Springfield, Illinois, this 16th 20 day of October, 1918.

FRANK GUY.
